UNITED STATES PATENT OFFICE.

EDWARD C. PELKEY, OF PORTLAND, MAINE.

DESIGN FOR COMBINED TABLE AND LAMP.

Application filed September 21, 1923. Serial No. 7,285. Term of patent 7 years.

To all whom it may concern:

Be it known that I, EDWARD C. PELKEY, a citizen of the United States, residing at Portland, in the county of Cumberland and State of Maine, have invented certain new, original, and ornamental Design for Combined Table and Lamp, of which the following is a specification, reference being had to the accompanying drawing, forming a part thereof.

The figure of the drawing is a perspective view of my new combined table and lamp.

I claim:—

The ornamental design for combined table and lamp as shown.

EDWARD C. PELKEY.
